UNITED STATES PATENT OFFICE

RALPH W. KURTZ, OF COSHOCOTON, OHIO, ASSIGNOR TO JAMES B. CLOW & SONS, OF CHICAGO, ILLINOIS, A CORPORATION OF ILLINOIS

RADIATOR

Application filed January 2, 1931. Serial No. 506,073.

This invention relates to radiators and improvements therein and is illustrated herein in connection with a radiator of the same general type as that disclosed in United States Letters Patent No. 1,681,173 granted August 21, 1928, upon application of E. V. Daily and assigned to the assignee of the instant application.

Radiators of the type described in the aforesaid patent comprise, generally speaking, a plurality of aligned sections which are connected with one another to form a water circulating chamber in the upper part of the radiator proper and a combustion chamber in the lower part of the radiator. The structure is self-contained in the sense that it is not connected by pipes or otherwise with a central heating system but employs a burner within its combustion chamber for heating the water and need only be connected with a suitable source of fuel supply to be operative. It is customary in such radiators to insert a fuel burner extending lengthwise of the combustion chamber and to form in the bottom of the combustion chamber an opening for the admission of air to support the combustion.

The patent mentioned above is directed to the important feature of disposing a baffle above the air inlet opening to prevent refuse from the burner falling through the opening and reaching the floor of the room in which the radiator is placed. The present invention has for its object the improvement of the baffle arrangement disclosed in said patent.

In accordance with the present invention, a plurality of air inlet openings are formed within the bottom of the radiator and baffles are disposed above the openings in such a manner as to divide the incoming air into a plurality of streams one of which serves as a primary air stream and the other as a secondary air stream.

Other objects and features of the invention will become apparent from a reading of the following specification in the light of the appended drawings, in which

Figure 1 is a somewhat diagrammatic view, shown partly in section, of a radiator com-

prising a plurality of sections embodying the invention.

Figure 2 is a view in side elevation of a single section equipped in accordance with the present invention.

Figure 3 is a view in section taken along the line 3-3 of Figure 2, and

Figure 4 is a bottom plan view of the section shown in Figure 2.

Referring to the drawings, there is shown in Figure 1 a radiator comprising a plurality of sections 2, 4, 6, 8 and 10 of the type shown in Figure 2. Each of these sections comprises, as disclosed in Figure 2, a water chamber 12 located within the upper portion of the section and a combustion chamber 14 formed within the lower portion thereof. The sections are joined together by means of nipples 16 and 20 projecting laterally from the sides of the water chamber and by means of laterally extending side walls 18 projecting from the combustion chambers 14. Thus, when a radiator is assembled, the water chambers of the adjacent sections are in communication with one another by means of the nipples 16 and 20 and the combustion chambers of the several sections are aligned with one another and united to form a single large chamber extending throughout the length of the radiator in the bottom portion thereof.

During the use of the radiator an elongated burner 21 is inserted lengthwise of the combustion chamber 14 of the radiator and is supplied with a suitable quality and quantity of fuel for heating the water within the water chamber. To insure proper combustion it is necessary to supply air to the burner and in accordance with the present invention such air is supplied in the following manner.

The combustion chamber 14 formed in the bottom of each radiator section comprises a front wall 22, a rear wall 24 and a bottom wall 26. The bottom wall is provided with a plurality of air inlet openings 28 and 30 disposed upon opposite sides of the center of the bottom wall and in operation air flows through the openings 28 and 30 and mingles with the fuel issuing from the burner to assure proper combustion.

As disclosed in Figures 2 and 3 baffles 32

and 34 are disposed above the air inlet openings 28 and 30 and serve to prevent refuse from the burner escaping through the openings. As shown, the baffles comprise horizontally extending portions and vertically extending portions 36 and 38, said portions being spaced respectively from the bottom wall and the front and rear walls of the combustion chamber, and having their inner ends spaced from one another to provide a central opening 40 between the baffles.

In operation, air flowing through the openings 28 and 30 strikes the baffles 32 and 34 and is divided into a plurality of streams, one of which flows through the central opening 40 and thence immediately to the burner, whereas, the remaining streams flow through the passageways defined by the front and rear walls 22 and 24 of the combustion chamber and the vertically extending portions 36 and 38 of the baffles. As the remaining air streams reach the top of the vertically extending portions of the baffles they flow inwardly above the burner and further support the combustion of the fuel.

In the sense that the air stream flowing through the opening 40 is the first to reach the burner it may be considered for purposes of description the primary air stream and the remaining streams which flow upwardly through the vertical passageways and are the last to be added to the combustible mixture may be considered as secondary air streams. The feature of dividing the incoming air into primary and secondary air streams is desirable and increases the efficiency of the radiator.

Although as illustrated herein each section is formed with openings confined within the bottom wall of the combustion chamber, it is to be appreciated that elongated openings extending completely through the bottom wall and disposed lengthwise of the radiator might also be provided. In other words, as herein disclosed, there is provided a series of air openings extending lengthwise of the bottom wall of the radiator but the openings in each series might within the contemplation of the applicant be changed into one long opening without departing in any wise from the spirit of the invention herein. It is likewise to be understood that other modifications and rearrangements of the parts may be made without departing from the true scope of the invention as described herein and as set forth in the appended claims.

Having thus described the invention, what I claim as new and desire to secure by Letters Patent of the United States is:

1. A radiator section having a walled combustion chamber formed in the bottom thereof for receiving a burner, said chamber comprising a bottom wall, a front wall, and a rear wall, the bottom wall having an air inlet opening, and a baffle located above the open-

ing, said baffle being constructed and arranged to divide the incoming air and to deliver the same to the burner in a primary air stream and a secondary air stream.

2. A radiator section having a walled combustion chamber formed in the bottom thereof, said chamber comprising a horizontal bottom wall, a vertical front wall, and a vertical rear wall, the bottom wall having an air inlet opening, and a baffle located above the opening, said baffle having a horizontal portion and a vertical portion which are respectively spaced from and parallel to the bottom wall and a vertical wall of the combustion chamber.

3. A radiator section having a walled combustion chamber formed in the bottom thereof, said chamber comprising a bottom wall, a front wall, and a rear wall, the bottom wall having air inlet openings on opposite sides of the center thereof, and baffles disposed above said openings, said baffles having horizontal and vertical portions respectively spaced from and parallel to the bottom wall and the front and rear walls of the combustion chamber.

4. A radiator comprising, in combination, a plurality of aligned and communicating sections, a combustion chamber formed in the lower portion of the radiator and having a burner therein, said combustion chamber having air inlet openings extending lengthwise of its bottom wall upon opposite sides of the center thereof, and baffles disposed above said openings, said baffles having a central orifice therein for delivering primary air to the burner and providing a plurality of side orifices for delivering secondary air thereto.

5. A radiator comprising, in combination, a plurality of aligned and communicating sections, a combustion chamber formed in the lower portion of the radiator and having a burner therein, said combustion chamber having an air inlet opening in the bottom wall thereof, and a baffle disposed above said opening, said baffle having a central orifice positioned in staggered relation with respect to the air inlet opening, whereby the baffle divides the air flowing through the air inlet opening into primary and secondary air streams.

6. A radiator comprising, in combination, a plurality of aligned and communicating sections, a combustion chamber formed in the lower portion of the radiator and having a burner therein, said combustion chamber having air inlet openings extending lengthwise of the bottom wall of the combustion chamber upon opposite sides of the center, and a baffle having a central orifice disposed above said openings and being constructed and arranged with respect to the walls of the chamber to provide channels, said baffle dividing the air flowing through the air inlet openings into a primary air stream delivered to the

burner from the central orifice and secondary air streams delivered thereto by the channels.

7. A radiator comprising, in combination, a plurality of aligned and communicating sections, a combustion chamber formed in the lower portion of the radiator and having a burner therein, said combustion chamber having air inlet openings extending lengthwise of the bottom wall thereof upon opposite sides of the center, and a plurality of baffles for said openings, said baffles comprising horizontal portions disposed above the air inlet openings, and vertical portions extending upwardly from the outer edges of the horizontal portions.

Signed at Coshocton, Ohio, this 20 day of Dec., 1930.

RALPH W. KURTZ.
